UNITED STATES PATENT OFFICE.

JOHN E. DOODY, OF TORONTO, ONTARIO, CANADA, ASSIGNOR TO UNDERWOOD TYPE-WRITER COMPANY, OF NEW YORK, N. Y., A CORPORATION OF DELAWARE.

TYPEWRITING MACHINE.

Application filed September 25, 1920. Serial No. 412,756.

To all whom it may concern:

Be it known that I, JOHN E. DOODY, a subject of the King of Great Britain, residing in the city of Toronto, Province of Ontario, Dominion of Canada, have invented certain new and useful Improvements in Typewriting Machines, of which the following is a specification.

This invention relates to collating devices, 10 and especially those adapted for use with round-platen machines, in adjusting superposed sheets to the printing point in certain relation to one another. It very frequently happens that sheets of different sizes must 15 be used, and it is often found desirable to retain one sheet in the machine while changing the second. This occurs where a ledger-sheet is used in connection with a statement. The latter is generally smaller, and the items 20 of several statements are entered upon a single ledger-sheet.

One object of the present invention is to provide collating means so that two sheets of different sizes may be inserted and guided 25 in the machine and adjusted relatively to each other.

A feature of this invention is the provision of such collating means in connection with the ordinary paper-table such that one 30 of the guides shall be an extension of the paper-table and the other guide shall operate on the paper-table within the limits of the first guide.

Another object is to provide means where- 35 by a wide sheet may be held in position while a narrow sheet is being withdrawn and a substitute narrow sheet inserted in its place, and adjusted relatively to the wide sheet.

40 Other features and advantages will hereinafter appear.

In the accompanying drawings,

Figure 1 is a front view of the device applied to a machine of which the platen-structure and paper-rest are shown, two sheets of different width being outlined in dotted lines in position with respect to the chutes.

Figure 2 is a section on the line 2—2 of Figure 1.

50 Figure 3 is a perspective view of the device shown in Figure 1.

Figure 4 is a view of the outer or wide chute drawn to smaller scale, and detached from the machine.

55 There is illustrated the usual platen 1,

mounted upon a shaft 2 pivoted in the side walls 3 of the ordinary typewriter carriage. The platen is provided with the usual releasable pressure-rolls 4, 5, to run upon the bottom of the platen, apron 6, and rear paper-table 7, mounted in the carriage with respect to the platen in the ordinary manner. The upper edge of the paper-table ends in a substantially semi-cylindrical upper edge part 10, forming a hollow interior 65 within which is mounted the supporting means for the inner, or narrow, paper-guide or chute in the following manner:

A rod 11, threaded at its ends, is inserted in the hollow interior thus formed by the 70 semi-cylindrical part 10 of the paper-table, and is provided with end screws having grooved portions 12 which fit into the hollow of the semi-cylindrical surface, the heads 13 of the screws abutting against the 75 ends of the paper-table and fixing the rod in position. Before attaching the end screws there are slid upon the rod the two interior guides which form the inner or narrow chute. Each guide comprises a floor-portion 80 14 and an upstanding, sheet-guiding member or side wall 15. The guides or guide-members are adjustably supported on the rod 11 by means of collars 16 slidable on the rod within the hollow of the edge portion 10. Rigid with the collar is a semi-cylindrical top extension 19 of the floor-portion 14 of the guides, which is of a radius 85 greater than that of portion 10 and adapted to encircle the latter, around which it is bent flatwise. Adjusting screws 17 pass through the collars 16 and abut against a flattened portion 18 of the rod 11 to clamp the guides in position.

From the above description, it will be 90 seen that the collar 16 may slide on the rod 11 within the semi-cylindrical portion 10 of the paper-table 7, and carries a member 19, forming an integral part of the guide, which encircles the portion 10. The connection between the collar 16 and member 19 slides in the open space provided by the portion 10. The guides may be moved on the paper-table 7 to different positions along the platen 1 and clamped by means 95 of screws 17, and thus constitute the inner or narrow chute, comprising the two separate parts or members mounted for independent adjustment along the platen.

100 The outer guide, or wide chute, comprises 110

a substantially U-shaped frame 41 having upstanding sheet-guiding side walls or members 42 terminating in tapered points 38, the ends being hollowed out as at 39, 5 and having a flat floor-portion, or connecting member, 43, forming an upper extension of the paper-table 7 and coming down in close proximity to the cylindrically-curved upper edge part 10 of the paper-table. A tie-rod 45 fixed in the end walls of the carriage is here shown passing through the side walls 42 of the frame near their forward edge. The walls 42 are provided with hubs 44 through which pass screws 49 enabling the frame to be adjusted in position along the tie-rod, and consequently 15 along the platen. The usual spring clips or paper-fingers, ordinarily mounted on the tie-rod, are here replaced by spring clips 20 or paper-fingers 46 mounted upon a U-shaped bar 47, the ends of which are adjustably secured at 48 to the side walls 42. The clips 46 project over the edge of the 25 apron 6, and have their ends turned slightly upwards so as to catch the sheet as it moves around the platen and direct it backwards within the limits of bar 47.

The manner of mounting of the frame or wide chute 41 upon the machine will be ap- 30 parent. The frame 41 having been mounted on the tie-rod 45, the said rod is inserted in the end walls 3 and fixed in position, the pointed ends 38 of the side walls passing between the platen and the paper-table until the edge 39 lies adjacent the 35 platen. The connecting-member 43 forms a continuation of the paper-table 7 which fits into the opening 52 in the U-shaped frame. Notches 53 are provided in the 40 lower edge of each wall 42 where the wall intersects the cylindrically-curved portion 10 of the paper-table. Other notches 54 may be provided where the walls overlie the hinged-joint between the apron and the 45 paper-table (in machines where such connection is employed). The spring paper-fingers 46 are adjusted to rest on the platen to engage the side margins of wide record-sheets to hold them against the platen. 50 Let it be assumed that a wide ledger-sheet has been inserted in the wide chute or guide 41 and it is desired to enter the items of several narrow statements. The pressure-rolls are released in the ordinary manner, the springs 46 holding the ledger-sheet 55 temporarily in position. The statement and carbon-sheet are then introduced through the rear, the ledger-sheet and statement aligned as desired, by adjusting the narrow statement-sheet over the wide 60 record-sheet, and the pressure-rolls applied. The process is repeated where new statements are inserted, but it is desired to maintain the same ledger-sheet. The various 65 sheets and statements may be provided with

perforations in register to aid in the aligning process.

It is apparent that the device as described above is extremely simple, may be readily applied to the ordinary typewriter 70 without any substantial change in structure, and provides two efficient co-operating guides or chutes, for guiding wide and narrow sheets with the narrow sheet overlying the wide sheet on the platen, together with 75 means for holding a wide sheet while a narrow sheet is adjusted thereover.

The wide sheet overlies and covers up the narrow chute, but is itself guided by the very high side walls of the broad chute, the 80 latter extending back far beyond the narrow chute, so as to be capable of controlling broad ledger-sheets having considerable length, while the narrow chute is relatively close to the platen, for controlling relatively 85 short and narrow statements.

Variations may be resorted to within the scope of the invention, and portions of the improvements may be used without others.

Having thus described my invention, I 90 claim:

1. In a typewriting machine, the combination with a cylindrical platen, of means at the introductory side of the platen for guiding thereto a wide sheet and a narrow sheet 95 to pass around the platen outside of the wide sheet, said guiding means comprising a paper-table, side gages adjustable thereacross to correspond to the width and position of the narrow sheet and forming with 100 the paper-table a narrow chute, and a wide chute, to guide the wide sheet over said narrow chute and the sheet therein, comprising side walls of greater height than the side gages and having their forward ends resting on said paper-table to form therewith the front portion of the wide chute, and a 105 floor connecting the rear portions of said side walls and serving as an extension of the paper-table. 110

2. In a typewriting machine, the combination with a cylindrical platen, of a paper-table at the introductory side thereof, opposed side gages on said paper-table, said gages being mounted at the upper edge of 115 said paper-table for adjustment laterally along said table and co-operating therewith to form a chute, and an outer chute having sides higher than said side gages and having its floor cut away at its forward end so that the paper-table may co-operate with the forward ends of the sides to serve as the floor of the forward part of the chute, the floor of the rear portion of the chute serving as an extension of the paper-table and being 120 spaced from the rear edge thereof sufficiently to permit adjustment of the side gages to vary the width and position of the inner chute. 125

3. In a typewriting machine, the combi- 130

nation with a cylindrical platen, of a sheet-collating device therefor comprising a wide chute at the introductory side of the platen for one work-sheet, said chute having a 5 transverse slot in its floor, and opposed side gages adjacent said slot and forming with the bottom of the wide chute a narrow chute for a work-sheet collated with the first sheet, said side gages having portions projecting 10 through said slot and being mounted for adjustment along said slot to vary the width of the narrow chute and its location transversely of the wide chute, said wide chute having side walls substantially higher than 15 said gages and of sufficient height to guide a wide sheet that overlies said gages, said wide and narrow chutes being co-operative to collate a wide work-sheet and a narrow work-sheet at different relative widthwise 20 adjustments, and to collate a wide work-sheet with narrow work-sheets of various widths.

4. In a typewriting machine having a carriage, said carriage having end walls, the 25 combination with a platen and a paper-table adjacent the platen mounted in said carriage, and a tie-rod between the end walls of the carriage, of a paper-chute positioned on the paper-table and having vertical end 30 walls, and a connecting floor-portion between said end walls forming an extension of said paper-table, said tie-rod passing through the end walls of said chute, means for fixing said chute in position upon said 35 tie-rod, and guide-members mounted on the paper-table within said chute and forming a second chute for positioning a sheet relatively to the first chute.

5. In a typewriting machine having a 40 carriage, the combination with a platen and a paper-table adjacent the platen mounted in said carriage, and pressure-rolls adapted to press against said platen, of a paper-chute positioned on the paper-table and having vertical end walls, and a connecting floor-portion between said end walls forming an extension of said paper-table, guide-members mounted on the paper-table within said 45 chute and forming a second chute for positioning a sheet relatively to the first chute, a U-shaped bar having its arms adjustably connected to said end walls, and spring members on said U-bar pressing against said platen to hold a sheet in position when said 50 pressure-rolls are released.

6. In a typewriting machine having a carriage, said carriage having end walls, the combination with a platen and a paper-table adjacent the platen mounted in said carriage, and a tie-rod between the end walls of the carriage, of a paper-chute positioned on the paper-table and having vertical end walls, and a connecting floor-portion between said end walls forming an extension 55 of said paper-table, said tie-rod passing

through the end walls of said chute, means for fixing said chute in position upon said tie-rod, and guide-members adjustably mounted on the paper-table for movement longitudinally of the platen and forming a 70 second chute for positioning a sheet relatively to the first chute.

7. In a typewriting machine having a carriage, the combination with a platen and a paper-table adjacent the platen mounted in 75 said carriage, of a paper-chute positioned on the paper-table and having vertical end walls, the front of said end walls being cut away to form a concave portion fitting the surface of the platen, a connecting portion 80 between said end walls forming an extension of said paper-table, and guide-members mounted on the paper-table within said chute and forming a second chute for positioning a sheet relatively to the first chute. 85

8. In a typewriting machine having a carriage, the combination with a platen and a paper-table adjacent the platen mounted in said carriage, pressure-rolls adapted to press against said platen, and a tie-rod between the end walls of said carriage, of a paper-chute positioned on the paper-table and having vertical end walls, and a connecting floor-portion between said end walls forming an extension of said paper-table, 90 said tie-rod passing through the end walls of the chute, means for fixing said chute in position upon said tie-rod, guide-members mounted on the paper-table within said chute and forming a second chute for positioning a sheet relatively to the first chute, 95 a U-shaped bar having its arms adjustably connected to said end walls, and spring members on said U-bar pressing against said platen to hold a sheet in position when said pressure-rolls are released. 100

9. In a typewriting machine having a carriage, the combination with a platen and a paper-table adjacent the platen mounted in said carriage, pressure-rolls adapted to 110 press against said platen, and a tie-rod between the end walls of said carriage, of a paper-chute positioned on the paper-table and having vertical end walls, and a connecting floor-portion between said end walls forming an extension of said paper-table, 115 said tie-rod passing through the end walls of the chute, means for fixing said chute in position upon said tie-rod, guide-members adjustably mounted on the paper-table with- 120 in said chute for movement longitudinally of the platen and forming a second chute for positioning a sheet relatively to the first chute, a U-shaped bar having its arms adjustably connected to said end walls, and spring members on said U-bar pressing against said platen to hold a sheet in position when said pressure-rolls are released. 125

10. In a typewriting machine having a carriage, the combination with a platen and 130

a paper-table adjacent the platen mounted in said carriage, said paper-table having a semi-cylindrical upper edge, of a rod attached to said paper-table beneath said edge, 5 a collar slidable on the rod and also beneath said edge, a paper-guide resting on said paper-table and comprising a floor-portion, an upstanding end wall, and a substantially cylindrically-curved top extension of 10 said floor-portion bent flatwise around and encircling said semi-cylindrical upper edge and attached to said collar.

11. In a typewriting machine having a carriage, the combination with a platen and 15 a paper-table adjacent the platen mounted in said carriage, said paper-table having a semi-cylindrical upper edge, of a rod attached to said paper-table beneath said edge, said rod having a portion of its periphery 20 flattened, a collar slidable on the rod and also beneath said edge, a paper-guide resting on said paper-table and comprising a floor-portion, an upstanding end wall, and a substantially cylindrically-curved top ex- 25 tension of said floor-portion bent flatwise around and encircling said semi-cylindrical upper edge and attached to said collar, the connection between said extension and said collar being adapted to move in the 30 cut-away portion opposite the semi-cylindrical upper edge, and means for adjusting the position of said collar along said rod to adjust the paper-guide along the platen comprising a screw passing through said 35 collar and abutting against the flattened portion of the rod.

12. In a typewriting machine, the combination with a revolute platen, of a wide chute at the introductory side of the platen 40 having side walls or members to engage the edges of a wide record-sheet for guiding it to the platen, a narrow chute within the wide chute between the side walls or members thereof and having side walls or members of less height than the side walls or 45 members of the wide chute, so that the wide record-sheet may be guided by the side walls or members of the wide chute over the side walls or members of the narrow chute, and so a narrow sheet may be guided by the narrow chute to overlie the wide record-sheet on the platen, means for affording a lateral adjustment of the narrow chute while the wide chute remains stationary, 50 releasable means co-operative with the bottom of the platen to line-feed all the sheets, and paper-fingers arranged at the delivery side of the platen to press the side margins of the wide record-sheet against the platen and hold it while the narrow sheet is adjusted thereover when said 55 releasable means are released.

13. In a typewriting machine, the combination with a revolute platen, of a wide chute at the introductory side of the platen 60

having side walls or members to engage the edges of a wide record-sheet for guiding it to the platen, a narrow chute within the wide chute between the side walls or members thereof and having side walls or members of less height than the side walls or members of the wide chute, so that the wide record-sheet may be guided by the side walls or members of the wide chute over the side walls or members of the narrow chute, and so a narrow sheet may be guided by the narrow chute to overlie the wide record-sheet on the platen, releasable means co-operative with the bottom of the platen to line-feed all the sheets, and paper-fingers arranged at the delivery side of the platen to press the side margins of the wide record-sheet against the platen and hold it while the narrow sheet is adjusted thereover when said releasable means are released, said narrow chute comprising a pair of separate parts or members mounted for lateral adjustment independently of the wide chute, 85

14. In a typewriting machine, the combination with a revolute platen, of a wide chute at the introductory side of the platen having side walls or members to engage the edges of a wide record-sheet for guiding it to the platen, a narrow chute within the wide chute between the side walls or members thereof, so that the wide record-sheet guided by the side walls or members of the wide chute may pass over the narrow chute, said narrow chute having side walls or members to engage the edges of a narrow sheet for guiding the narrow sheet to overlie the wide record-sheet on the platen, releasable means co-operative with the bottom of the platen to line-feed all the sheets, and paper-fingers at the delivery side of the platen carried by the wide chute to press the side margins of the wide record-sheet against the platen and hold it while the narrow sheet is adjusted thereover when said releasable means are released, said wide chute being 100 mounted for adjustment along the platen together with the paper-fingers carried thereby, 105

15. In a typewriting machine, the combination with a revolute platen, of a wide chute at the introductory side of the platen having side walls or members to engage the edges of a wide record-sheet for guiding it to the platen, a narrow chute within the wide chute between the side walls or members thereof, so that the wide record-sheet guided by the side walls or members of the wide chute may pass over the narrow chute, said narrow chute having side walls or members to engage the edges of a narrow sheet for guiding the narrow sheet to overlie the wide record-sheet on the platen, releasable means co-operative with the bottom of the platen to line-feed all the sheets, and paper-fingers at the delivery side of the 120 platen, 125

platen carried by the wide chute to press the side margins of the wide record-sheet against the platen and hold it while the narrow sheet is adjusted thereover when said 5 releasable means are released, said narrow chute comprising a pair of separate parts or members mounted for adjustment to different distances apart for guiding narrow sheets of different widths; and also adjustable to different distances from the side walls or members of the wide chute to vary the position of a narrow sheet relatively to the wide record-sheet, and said wide chute being mounted for adjustment along the platen together with the paper-fingers carried thereby.

16. In a typewriting machine, the combination with a traveling carriage, a revoluble platen mounted therein, and a rear paper-table mounted on the carriage, of a wide chute mounted on the carriage for adjustment along the platen, and having side walls or members to engage the edges of a wide record-sheet for guiding it to the platen 20 over the rear paper-table, a narrow chute mounted on the rear paper-table to rest thereon between the side walls or members of the wide chute, so that the wide record-sheet guided by the side walls or members of the 25 wide chute may pass over the narrow chute, said narrow chute having side walls or members to engage the edges of narrow sheets for guiding the narrow sheets over the rear paper-table to the platen to overlie the wide 30 record-sheet thereon, said narrow chute comprising a pair of separate parts or members mounted for independent adjustment on the rear paper-table along the platen to different distances apart and to different distances 35 from the side walls or members of the wide chute, for guiding narrow sheets of different widths and for varying the position of the narrow sheets relatively to the side record-sheet, releasable means co-operative with the 40 bottom of the platen to fine-feed all the sheets, and paper-fingers at the delivery side of the platen carried by and adjustable along the platen with the wide chute to press the side margins of the wide record-sheet against 45 the platen and hold it while a narrow sheet 50 is adjusted thereover when said releasable means are released.

17. In a typewriting machine having a carriage, the combination with a platen and 55 a paper-table adjacent the platen mounted in said carriage, said paper-table having a semi-cylindrical upper edge, of a rod attached to said paper-table beneath said edge, a collar slidable on the rod and also beneath said 60 edge, a paper-guide resting on said paper-table and comprising a floor-portion, an up-standing end wall, a substantially cylindrically-curved top extension of said floor-portion bent flatwise around and encircling said 65 semi-cylindrical upper edge and attached to

said collar, and a second paper-guide having a floor-portion forming an upper extension of said paper-table in close proximity to said semi-cylindrical upper edge of the paper-table.

18. In a front strike typewriting machine, the combination with a revoluble platen and a platen-frame, of a wide introductory paper-chute having side walls to confine wide ledger sheets and extending back from the platen, side guides forming a chute for a narrow work-sheet mounted between said side walls of the wide chute, said side guides being located intermediate the platen and the rear end of the wide chute, and said side walls of the main chute being substantially higher than said guides, to guide a wide ledger-sheet which overlies said guides, means at said platen to detain said wide ledger-sheet during the removal of the narrow work-sheet and its replacement by a fresh narrow sheet, and releasable feeding means to press the work-sheets against the under side of the platen, said wide chute and said narrow chute being adjustable relatively to each other.

19. In a front-strike typewriting machine, the combination with a revoluble platen and a platen-frame, of a wide introductory paper-guide comprising side walls to confine wide ledger-sheets, said walls extending back from the platen, side guides for a narrow work-sheet forming a narrow chute mounted between said side walls of the wide guide, said side guides being located intermediate the platen and the rear end of the wide guide, and said walls of the wide guide being substantially higher than said side guides of the narrow chute to guide a wide ledger-sheet which overlies said narrow chute, means at the delivery side of the platen and having greater separation than said side guides of said narrow chute, for retaining by its side margins a wide ledger-sheet during the removal of the narrow work-sheet and its replacement by a fresh narrow sheet, and releasable feeding means to press the work-sheets against the under side of the platen, said wide introductory paper-guide with said narrow chute and said retaining means being adjustable as a unit along the platen.

20. In a front strike typewriting machine, the combination with a revoluble platen and a platen-frame, of a sheet-collating device therefor comprising a wide introductory paper-chute having side walls to confine wide ledger-sheets and extending back from the platen, side guides for a narrow work-sheet mounted between said side walls of the wide chute, said side guides being located intermediate the platen and the rear end of the wide chute, and said side walls of the main chute being substantially higher than said guides, to guide a wide ledger-

sheet which overlies said guides, means at the delivery side of the platen and having greater separation than said side guides, for retaining by its side margins a wide ledger-
sheet during the removal of the narrow work-sheet and its replacement by a fresh narrow sheet, and releasable feeding means to press the work-sheets against the under side of the platen, said side guides being in-
dividually adjustable longitudinally of the

platens, and co-operative with said side walls to collate a wide work-sheet and a narrow work-sheet at different relative widthwise adjustments, and to collate a wide work-sheet with narrow work-sheets of various widths.

JOHN E. DOODY.
